RAILROAD TRACK WEEDING CAR

Filed Aug. 4, 1930

UNITED STATES PATENT OFFICE

XAVIER LATTY, OF PARIS, FRANCE

RAILROAD TRACK WEEDING CAR

Application filed August 4, 1930, Serial No. 473,055, and in France July 24, 1930.

The present invention relates to the type of railroad track weeding cars or trucks comprising a series of rows of pivotally mounted weeders adapted to loosen and weed the ballast or metal of the track or road bed and to pass yieldingly over the railroad ties or sleepers whilst the car runs on the rails.

The primary object of the invention is to provide an improved weeding car or truck of the aforesaid type wherein the weeders are adapted to loosen and weed the ballast of the track right to the sub-grade formation thereof whilst automatically passing over the ties without damaging them.

15 A further object of the invention is to provide a weeding car wherein the weeders are so arranged and acted upon by springs as to readily permit the operator of the car to detect whether any wooden tie is in good condition by extracting of the bed of ballast any portion of tie which may have become rotten in the long run.

A still further object of the invention is to provide a weeding car wherein certain of the weeders are so disposed as to loosen and weed the ballast adjacent the flanges or feet of the rails whilst automatically passing off the ties without engaging with the portion of the rails secured thereto or with the chairs, screws, spikes, clips or other fittings by means of which said rail portions are usually secured to the ties.

25 Still a further object of the invention is to provide a weeding car comprising plow-like delvers adapted to loosen and weed the sloping sides of the road bed in the same weeding operation.

Still another object of the invention is to 30 provide a weeding car comprising, in combination with the foregoing features, an improved mechanism whereby an operator can lift or lower the whole set of weeders single-handed and adjust the working depth of the weeders in view of weeding the ballast to the desired extent or depending upon the thickness of the ballast or metal of the track.

35 Still a further object of the invention is generally to facilitate and cheapen the construction and operation of the aforesaid type

of weeding cars utilizable on railroads no matter what their gauge may be.

For a more detailed understanding of the invention, reference may be had to the accompanying drawing wherein is shown by 55 way of example and diagrammatically one practical form that the improved track weeding car may assume, this drawing being an elevational view partly in section of the car considered in its entirety, assuming its weeders to be in operating positions.

The weeding car may be power-driven or adapted to be pushed or towed by a locomotive or coupled to a train.

1 A designates the frame or chassis of the 65 car of usual girder structure provided at its respective ends with end sills 2 on which are riveted standards 3 of known construction. 4, 4 designate the wheels rotatably carried in conventional bearings 5, 5 supported by 70 rugged straps 6, 6 riveted to the girders of the frame 1. A footboard 7 is bolted as at 8 to each girder 1 for a ready access of the platform upon which the operator can stand.

Each girder 1 is fitted in the present embodiment of the invention with a pair of longitudinally spaced depending brackets 9, 10 to which are respectively bolted or riveted a pair of U-shaped joists 11, 12 which are similarly secured to transversely aligned 80 brackets (not shown) carried by the girder on the opposite side of the car. Upon the lower leg of the joists 11, 12 are rigidly secured lugs 13, 13' carrying pivots 14, 14' on which are pivotally supported intermediate their ends rows of two-armed levers 15, 15' to the longer arms of which are pivotally supported as at 16, 16' upright web-like shares 17, 17'.

Each share is fitted on a projection of the lower portion of its forward edge with a bifurcated guard 18 or 18' removably secured thereto for example by rivets as at 19, 19' and advantageously made of a highly hard steel or like material. The purpose of these guards 18, 18' is to take the stress due to the repeated knocks against the ties T while the weeding car travels on the rails R and weeds the ballast B. The repetition of such knocks merely wears out the guards 18, 100

18' in the long run without abrading the shares 17, 17' and fresh guards may be substituted for the worn out ones when required.

Adjacent its lower end each share 17 or 17' is fitted with a transverse knife 20 or 20' extending on both sides thereof and having a sharp fore edge as shown for cutting down the weeds in proportion as the shares make their way through the ballast B and thus loosen it, as will be readily understood.

As above-stated, each shaft 14 or 14' is provided with a row of levers 15 or 15' so that the ballast is loosened by rows of shares 17 or 17' while the weeds are cut down by two rows of knives 20 or 20'. The number of such rows might of course be larger than two. The shares and knives are in staggered relation from one row to another and the shares 17' and knives 20' are so arranged in pairs in the transverse direction as to loosen and weed the ballast B adjacent the rails R, as will be described hereafter.

The shorter arm of each of the supporting levers 15, 15' is pivotally connected at its free end as at 21, 21' to a lug 22, 22' fitted with an upstanding rod 23 loosely engaged through the bored web of a cross-beam 24. Each rod 23 is screw-threaded at both ends and fitted at its top end with a nut 25 bearing upon a washer 26. Between the washer 26 and the top flange of the cross-beam 24 is imprisoned a powerful spiral spring 27. Each cross-beam 24 has an upstanding portion 24^a to which is pivotally connected as at 28 the lower end of a link 29 pivotally connected by a pin 30 at its upper end to a longitudinally extending connecting bar 31. On the pins 30 are pivotally connected the adjacent ends of links 32 pivoted at their other ends on pins 33 fixed on the girder 1 of the car frame.

This link structure is of course duplicated from one side of the car frame to the other, the two bars 31 which connect the links 29 and 32 pairwise being fixedly united by a cross joist 34 to an intermediate part of which is secured an upstanding rack 35 guided in a conventional way in a block 36 carried by the platform of the car and actuated by means of a hand wheel 37 through the intermediary of a pinion (not shown) this construction being easy to understand by anyone skilled in the art.

One of the share-carrying levers, to wit: the one designated by 15' has its longer arm formed in two portions: the portion 15' adjacent the shaft 14' being U-shaped at its free end to accommodate the other portion 15'', a swiveling joint being provided for permitting a side motion of the said lever portion 15''. Upon the axis 38 of the swiveling joint is coiled a spiral spring 39 having its convolutions extending laterally and adapted to hold the lever portions 15' and 15'' in substantial alignment.

On the extremity of the lever portion 15''

adjacent the pivotal pin 16' is journalled a roller 40 adapted to co-operate with an outwardly convexed cam surface provided on an upstanding rod 41 of flat shape bolted as at 42 to the girder 1. The cam rod 41 is of course duplicated from one side of the car to the other and the two cam rods 41 are riveted together as at 43.

On a pin 44 fixed upon the rear joist 11 is connected a rearwardly extending bar 45 the rear end 46 of which is handle-shaped and provided with a hook 47 for the insertion of the lower hooked extremity of a suspension rod 48 hooked up at its upper extremity to the end sill standard 3. Intermediate its ends the bar 45 is attached to the lower end of a depending chain 49 attached at its upper end to the free end of a bell crank lever 50 fulcrumed at 51 on a quadrant-shaped bow 52 secured upon the platform of the car, the upper extremity of the upstanding arm of the bell crank lever 50 being handle-shaped as shown at 53. The arcuate portion of the bow 52 is formed with a number of spaced holes 54 into any one of which can be inserted a pin 55 formed on or secured to the adjacent face of the lower arm of the bell crank lever 50 whereby said lever can be held in the required angular position and the height of the bar can be similarly adjusted.

Adjacent the rear end of the bar 45 is secured thereto a depending bar 56 carrying a lower angular bar 57 to which is riveted or similarly secured rigidly a plow-like delver 58 having a pointed fore end 59 adapted to dig through the sloping sides of the bank of ballast B as the car moves on the rails R in the direction shown by the arrow. The arrangement of the delvers 48 is of course duplicated from one side of the car to the other for permitting the delving action to take place on both sides of the car, no further description being however required for a proper understanding of the structure.

The operation of this improved track weeding car as above-described may be briefly described as follows:

After the car has been driven to the proper spot where the ballast of the railroad track requires loosening and weeding, said car is caused to travel on the rails R at the approximate speed of two to three miles an hour. The various contrivances carried by the car are then set in operation as follows:

By turning the hand wheel 37 in the proper direction, the rack 35 is lifted which raises the cross joist 34 and consequently the connecting bars 31 arranged on both sides of the car. The links 29 are thus also raised while the springs 27 are compressed. This results in lifting of the shorter arms of the weeder-carrying levers and lowering of their longer arms 15 and 15' with respect to the stationary shafts 14 and 14', the lifting or

lowering motions being of course transmitted to all the rows of weeders. Thus the lower ends of the shares 17, 17' penetrate into the ballast R. It will thus be understood that due to the car travelling along the rails R the ballast is loosened by the several shares and as their rows are arranged in staggered relation there is not a single transverse region of the ballast which escapes their 10 loosening action. At the same time, the knives 20 and 20' travelling through the mass of ballast but sheltered, as it were, by the protruding shares 17, 17' cut down all weeds, the latter being extirpated of the ballast 15 where they can be raked off or burnt away.

Due to the independent mounting of the weeders, each weeder works independently of the other weeders depending on the nature of ballast which it meets. As above-stated, 20 the action of the weeders 17' is to weed those parts of the ballast closely adjacent the rails which was not possible with prior constructions.

When a share 17 or 17' strikes a tie T by 25 its knocking guard 18 or 18', its supporting lever rocks about its pivot whereby said share together with its knife gently come out of the ballast B without any risk of their being caught whereafter they descend again 30 on the other side of the tie T, in the direction disclosed by the arrow, are again forced into the ballast B by the action of the spring 27 and can thus resume their loosening and weeding work without leaving any portion 35 of the ballast non-loosened or non-weeded.

The impact delivered by each share against a tie T through its guard is not normally sufficient for damaging a tie when in good condition but is nevertheless powerful enough 40 for readily showing that a wooden tie is rotten by rooting the most rotten portions thereof out of the ballast.

The row of shares 17' has its constitutive shares arranged, as above-stated, pairwise on 45 each side of the respective rails R for the purpose of loosening and weeding the ballast closely adjacent thereto and even thereunder, thus rooting out those weeds which with prior 50 constructions of weeding cars for use on railroads, remained alive in the vicinity of the rails. When any share such as 17' hits a tie T by its guard 18', the upward rocking motion of the supporting lever arm 15'-15" causes the side roller 40 to roll up along the 55 outwardly convexed cam surface 41 and thus to be diverted outwardly. As a result of this, the lever portion 15" is swiveled off sidewise to a corresponding extent whereby the share 17' and knife 20' can strike neither the 60 flange nor the head of the rail R, the convexity of the cam surface 41 being of course so reckoned as to divert the share 17' to a sufficient extent sidewise for preventing any contact between it and the rail.

65 The operation of the plow-like delvers

58-59 is easy to understand. As above-stated the purpose of these delvers is to loosen and eventually weed the sloping sides of the bank of ballast B. The vertical adjustment of such delvers can be readily carried out from the 70 lever 50 and as the handle 53 thereof is not far from the hand wheel 37, a single operator can operate both members. The lateral adjustment of the delvers is effected by means of the suspension rod 48 permitted by the 75 pivotal connection 44 which may be of a universal nature.

Numerous minor constructional details might be changed without departing from the spirit of the invention and the scope of 80 the appended claims.

What I claim and desire to secure by Letters Patent of the United States is:

1. A railroad track weeding car comprising, in combination, a girder frame, two pairs 85 of parallelogrammic links pivoted on both sides of the frame and connected by a transverse joist, a rack mechanism having a hand wheel located above the platform of the car for raising and lowering said transverse joist, a plurality of cross beams pivotally connected to the lower ends of said links, levers articulated upon said cross beams, compression springs between said cross beams and said 90 levers, shares connected to the ends of said levers remote from their articulations upon the cross beams and having transverse weeding knives, removable guards on the forward edges of the shares, a roller revolvably mounted on the free end of certain share-carrying 95 levers, an outwardly convexed cam bar depending from each girder of the frame and co-operating with the adjacent roller, a swivel joint intermediate the ends of the share-carrying lever fitted with a roller, a pair of 100 plow-like delvers located on both sides of the rear portion of the car frame, and vertically and laterally adjustable suspension means for 105 said delvers.

2. A railroad track weeding car comprising, in combination, a girder frame mounted 110 on wheels, two pairs of parallelogrammic links pivoted on both sides of the frame and connected by a transverse joist, a rack mechanism having a hand wheel located above the 115 platform of the car for raising and lowering said transverse joist, a plurality of cross beams pivotally connected to the lower ends of said links, rows of levers articulated upon 120 said cross beams, compression springs between said cross beams and said levers, upright shares connected to the ends of said levers remote from their articulations upon the cross beams and fitted at their lower ends with transverse weeding knives, removable 125 guards on the forward edges of the shares, a roller revolvably mounted on the free end of certain share-carrying levers located adjacent to the rails and on both sides thereof, an outwardly convexed cam bar depending from 130

each girder of the frame and co-operating with the adjacent roller, a swivel spring joint intermediate the ends of the share-carrying levers fitted with a roller, a pair of plow-like delvers located on both sides of the rear portion of the car frame, an adjustable bell crank lever journaled on the platform of the car and having its handle adjacent the rack operating hand wheel, means for angularly adjusting the position of said bell crank lever, a chain connecting said last-named lever with the corresponding delver, and means for laterally adjusting the position of said delvers.

15 In testimony whereof I have signed my name to this specification.

XAVIER LATTY.
